UNITED STATES PATENT OFFICE.

LORENZO DOW AND DANIEL POWERS, OF BOSTON, MASSACHUSETTS.

TYPE-DISTRIBUTING MACHINE.

SPECIFICATION forming part of Letters Patent No. 430,007, dated June 10, 1890.

Application filed March 27, 1889. Serial No. 304,943. (No model.)

To all whom it may concern:

Be it known that we, LORENZO Dow and DANIEL POWERS, citizens of the United States, residing at Boston, in the county of Suffolk and State of Massachusetts, have invented certain new and useful Improvements in Type-Distributing Machines; and we do hereby declare the following to be a full, clear, and exact description of the invention, such as will enable others skilled in the art to which it appertains to make and use the same.

Our invention relates particularly to an improvement upon a type-distributing machine invented by Lorenzo Dow, one of the inventors herein named, and patented December 11, 1888, No. 394,255. It refers chiefly to the mechanism of lifting from the galley and pushing forward the type to be distributed, and the ejection of the end type from the line in which it stands into a carrier, by which it is delivered into the mouth of the tube leading to its final receptacle.

Figure 1 is an elevation of our improved type-distributing machine; Fig. 2, a plan view of the same; Fig. 3, section of the machine on line $x-x$, Fig. 2, enlarged. Fig. 4 is a detail in cross vertical section to show the hammer and its operating mechanism. Fig. 5 is a plan view of the same, also showing a part of the type-carrier in position. Fig. 6 is a plan in detail, to show more particularly the shifting arrangement which is to effect the second step of the distribution. Fig. 7 is a detail in perspective, enlarged, of the galley and the mechanism for lifting the type to the channel. Fig. 8 is an enlarged detail of the stop which operates upon the crank. Figs. 9 and 10 are sectional views of the galley and the lifter. Fig. 11 is an enlarged perspective view of the mechanism for taking a single type from the channel and delivering it in one of the grooved plates intended for holding the type. Fig. 12 is a rear elevation of a few of the cam ends and the ends of the operating-levers. Fig. 13 is a perspective view, enlarged, of the mechanism for operating the hammer and the gate. Fig. 13^a is a detail. Figs. 14 and 15 are enlarged perspective views of parts of the gate, the hammer, and the type-channel. Fig. 16 is a perspective view of the parts of the gate. Fig. 17 is an end view, partly in section, on line $y-y$ of Fig. 6.

Fig. 18 is an enlarged sectional view of the grooved plate that receives the distributed type. Figs. 19 and 20 show method of connecting the elastic tubes to the grooved plate. Figs. 21 and 22 show method of attaching the upper end of the elastic tube to the switch-plate shown in Fig. 6. Fig. 23, Sheet 5, is a rear view of Fig. 6, to show how the switch-plate is supported. Fig. 24 is a sectional view of the spring in the drum operating to eject the type.

In the illustration similar letters refer to similar parts of the machine.

A is the frame of the machine.

B is the galley supported by the frame, upon which the dead matter to be distributed is placed.

C is a movable piece intended to be set to support the side of the type-column and adjustable to the width of said column; D, the channel into which the end or lowermost line of type on the galley is lifted.

E is a plate on which the type slide on their feet as they stand in the carrier, into which they have been thrust by the hammer beneath each carrier. At the point where the type is to leave it is an opening in the plate E, into which the type falls, the lower end of said carrier being open.

E² is a plate containing a series of channels arranged vertically under the openings into which the type falls from the carrier, which channels conduct them into the openings of the switch-plate E', through which they pass into the elastic tubes E³.

E' is a horizontal switch-plate, which serves as a continuation of the elastic tubes E³ and to support the same. This plate is adjustable to different positions, and is moved into the desired position at the will of the operator to present the mouths of the elastic tubes which are required to conduct the type in process of distribution to their proper receptacle.

E³ are elastic tubes, attached at their upper ends, as just described, to plate E', and at their lower end to the grooved plate F, designed to convey into the proper grooves thereof the type intended for the same.

In Fig. 7 the galley is shown set at such an angle that the dead matter will nearly slide down of its own weight as the lowermost line

is successively lifted to the channel D. Should the type not move freely, there may be used a weight or follower behind to urge it down. The piece C is movable, and used 5 to sustain one side of the type lying on plate B, and is adjustable to the width of the column of type, and is held in place by one end thereof passing round and under plate B, which forms the bottom of the galley, which 10 part is held in position by the set-screw c¹, Fig. 3, passing through the same and binding on the plate. c² is an enlarged bearing of the piece C, which slides on the end of the bottom plate B of the galley and serves to 15 keep the movable piece C parallel with the side of the galley, aiding the set-screw c¹ to hold the same in place.

D is the channel into which the type are lifted from the galley, extending from the 20 gate end, where the hammer operates to eject the end type, to and along the lower end of the galley to its outer edge. It is seen in Figs. 9 and 10 that the type in the galley rest against the movable piece D² at their lower 25 end. In Fig. 9 it will be seen that this piece is thinner at the upper edge than at the lower, and that there is a shoulder at D⁰. When this piece is depressed, the lowermost line of type is seen to have advanced and to rest on 30 this shoulder in Fig. 10. When the same is raised to its second position, (seen in Fig. 9,) it carries up the line of type resting upon the shoulder D⁰. When in this position, the shoulder D⁰ becomes a continuation of the bottom 35 of channel D. The remaining body of type stand, as seen in Fig. 9, in position to again move down upon the depression of D². This movement up and down of the piece D² (shown in section in Figs. 9 and 10) at the 40 will of the operator, to supply the type as fast as required in the distribution, is effected as follows:

In Fig. 7 is seen a rack attached to each 45 end of the piece D², (marked D³) which are actuated by the geared wheels D⁴, one at each end of the shaft D⁶. Partial rotation of these geared wheels is effected by the rack d, which engages with the right-hand pinion-wheel D⁴. This rack at its lower end is pivoted to one 50 end of the piece d⁴, Fig. 8. d⁴ is also pivoted at the other extremity to the frame A of the machine at d⁵. At the end d⁴ is seen a pin or small friction-wheel d¹³, that travels on the face of the eccentric cam d⁸. When the 55 crank d² is turned to the left, it rotates the shaft d⁰, carrying with it the cam d⁸, to which it is rigidly attached. This rotation carries down the free end of the piece d⁴, and with it the rack d. This rack, engaging with the 60 geared wheel D⁴, actuates it and the shaft D⁶, with the other wheel D⁴ at the opposite end. Both these geared wheels, engaging with the racks D³, raise them and the piece D², to which they are attached. This, as before described, carries up with it a line of type into the channel D. As the rotation of the handle d² continues it carries forward the cam d⁸ un-

til the point of it at d⁷ has passed off the small friction-wheel d¹³. d⁶ is a spring, one end attached to the frame A and the other end 70 thereof upon the piece d⁴ near its free extremity, to throw it up when the cam d⁸ at its point d⁷ has passed off the friction-wheel, which movement of the free end of d⁴ effects a reverse movement of the piece D², throwing 75 it down, so that the shoulder D⁰ again passes under a line of type, as seen in Fig. 10.

D¹¹, Fig. 7, is a sliding piece moving freely backward and forward within the channel D, and when the line of type has been raised is 80 standing in the channel D behind the said line. This piece D¹¹ is held from falling when the shoulder D⁰ descends to take the line of type, by a pin in the frame A, working in a groove D¹². Pivoted to the end of this piece 85 D¹¹, near its right-hand extremity, is the piece d⁹, the lower end of which is attached to the cam d⁸ by the stud or pin d¹¹, working in the slot d¹⁴ in the piece d⁴. When the shaft d⁰ is rotated by the crank d², as just described, the 90 cam d⁸, being firmly attached thereto, is rotated. Another small friction-roller on the pin d¹², traveling on the face of this cam d⁸, draws back the piece D¹¹ to allow the lifting of a new line of type into the channel D. 95 When the small friction-roller d¹² has passed the point d¹³ of the cam d⁸, the sliding piece D¹¹ is behind the line of type and in position to be moved forward, carrying the line of type just lifted from the galley into the channel D before it. This movement of pushing 100 forward the line of type is effected by a coiled spring within the drum D⁹. Around this drum a cord passes, and thence round the small guide-pulley D¹⁴, and thence to the right-hand end of the pusher D¹¹, where it is attached to the same by the pin D¹⁵. When the rotation of the cam d⁸ has retracted the pusher D¹¹, as just explained, to its limit of movement, it has acted against the coiled spring in 105 drum d⁹ to wind it up. When the roller d¹² has passed the point of the cam d¹³, the coiled spring is free to return the pusher D¹¹ to the position shown in Fig. 7. Every complete revolution of the shaft d⁰ therefore lifts up 110 a line of type into the channel D, and withdraws the pusher D¹¹, actuated as explained, and compresses the spring in the drum D⁹, which spring on its release draws forward 115 pusher D¹¹, and the line of type behind which it has taken its place, toward the hammer end of channel D; and this process of lifting and pushing forward a line is repeated as often as necessary to supply type in the channel D for the work of distribution. In order 120 that the handle d², actuating shaft d⁰, may be arrested at the right point, a stop c is provided. This stop is shown at c, Fig. 7, as a spring, one end of which is attached to the piece d⁴, the free end acting against the handle d² to limit its movement to a single rotation. Upon handle d² is a movable sleeve c', 125 Figs. 7 and 8, which the operator, when he grasps the handle d², pushes lightly toward 130

the arm c^3 , which connects the handle d^2 with the shaft d^0 . The movement of the sleeve c' toward the arm c^3 compresses the coiled spring c^2 and engages with the arresting-spring c and compressing it, thereby releasing the handle d^2 and allowing another revolution thereof.

Figs. 14, 15, and 16 show a part of the mechanism for pushing the end type standing in the channel D out from the line and into a carrier. As the line of type is pushed or fed forward, as just explained, its movement is arrested by the fixed end piece D^{00} , Fig. 14. H is the hammer. Preferably it has two faces, in order to give two points of contact with the type upon which it acts.

In Fig. 15 is seen the piece K, into which it is the office of hammer H to thrust the type at the end of the column. In Fig. 4 this hammer is seen to be pivoted to the piece H', which is attached to the frame A by the pivot A'. This hammer is actuated by the piece h^2 to thrust out the end type before it. The piece h^2 is connected at its other extremity to the arm h^3 , operated by the shaft h^4 , Figs. 11 and 13. This shaft h^4 is attached to the frame A and partially rotated to operate the hammer by the arm h^5 , Fig. 13, and by the piece h^6 , attached at the other extremity to the arm h^7 , actuated by the shaft h^8 . This shaft, supported in brackets A³ at each end, carries two arms H¹², which at their extremities carry the piece H⁴, Fig. 13. This piece or rod H⁴ lies below and at right angles to all the levers of the key-board and close against their under edge. When any key-lever H⁵ is depressed, it carries down with it this piece H⁴, and thus actuates the parts just described, and the hammer H throwing it forward and expelling the type standing before it. The coiled spring h^3 on the shaft h^4 returns the various parts to their former position, ready to thrust out another type by the depression of any key-lever. This hammer H was seen in Fig. 4 to be carried by the free end of the piece H', which is pivoted to the frame A at A'. Since the thickness of the body of the letters of a single font varies constantly from a hair to a capital W, it is obvious that the hammer must be made to adjust itself automatically to the thickness of the body of the end letter or space standing before it. This is effected by giving the hammer a lateral movement. How this is done will be seen in Fig. 13. Pivoted to the piece H' is the piece b, and this piece at its other extremity is pivoted to the arm b^2 at b^3 . The arm b^2 is actuated by the shaft b^4 , which at the other end is attached to the arm b^6 at b^5 . This arm is connected at its extremity with the piece b^7 and at the other end to the arm b^9 at b^8 . This arm is actuated by the shaft b^{10} . At b^{11} will be seen the piece b^{12} , firmly connected to this shaft. This piece b^{12} has a convex face, to which is shown to be attached the piece b^{13} by two screws. This allows, by tightening one screw and loosening the other, of adjusting the inclination of the piece b^{13} . The upper end of

b^{13} is shown as bent or cut, so as to present an inclined surface to the pivot, on which is mounted a small friction-roller. Each lever 70 of the key-board carries one of these pins.

In Fig. 13 the pin t' on the short key-lever H¹⁰ is a little farther from the fulcrum of this lever than the one t shown on H⁵, its adjoining long lever, this lever being cut away 75 to show its pin. The movement of the key downward causes this friction-roller to bear upon the inclined face of b^{13} at their point of contact and throw it forward. This movement of the upper end of b^{13} actuates the 80 shaft b^{10} , and through the mechanism just described moves the free end of the piece H', which carries the hammer H. The sole office of this short lever H¹⁰ is to operate the mechanism described to effect a movement differing in degree from that effected by the lever H⁵ adjacent to it. On one lever therefore it is only necessary that the pin t' should be set a little farther from the fulcrum H⁷ than the pin t on the other lever, the lever 90 H⁵ being broken away to cause a more or less movement of the arm b^{13} , against which they operate. By adjusting these pins so as to give such movement to b^{13} as to swing the hammer on the piece H' to cover the body of 95 the type standing before it, we effect the desired object. This adjustment will depend on the size of the letter the key represents, and is effected by the two adjusting-screws connecting the piece b^{13} to the curved face of 100 b^{12} . In the machine illustrated in the drawings we show, as in Fig. 2, a key-board with thirty keys and thirty supplemental keys carried by short levers H¹⁰. This number admits, then, of sixty adjustments, as each lever is adjusted to effect a movement of the piece 105 b^{13} through the pins t and t' according to the thickness of the body of the type represented by its key. We do not, however, limit ourselves to thirty keys and thirty supplemental 110 ones on the key-board.

Having shown how the hammer is made automatically to adjust itself to the thickness of the type-body to be pushed out, we now proceed to show how the opening or gate S, 115 through which the type are pushed out by the hammer, is made to automatically adapt itself to the thickness of the type that is to be passed from the end of the channel D to and into the carrier K.

In order that the type as it emerges from the channel D may not get out of position—that is, turn on its side—supports are required to hold it as it moves out. On one side in Fig. 14 it is apparent that the end piece D^{00} affords this support, extending, as is shown, to the left. Fig. 14 shows the supporting-piece of the other side of the type, which we call, "the gate." The piece H², swinging upon the pivot, carries at the free end two pieces s and s' of the gate S. In Fig. 14 these pieces s and s' are seen when in place to form a part of the side of the channel D, the ends s^3 moving in the slots s^4 and s^5 , Fig. 16. This is also seen in Fig.

15, where the end piece D^{00} is removed. If, then, the piece H^2 , carrying these pieces at its free end, be adjusted to move synchronously and equally with the movement of the hammer just described, we open and close the exit or channel through which the type pass into the carrier as required. We effect this, as seen in Figs. 14, 15, and 16, by connecting together the pieces H' and H^2 by the small piece s^2 . The same thing we also effect by making H' and H^2 a single piece, pivoted at one end at A' and the other end carrying both the hammer and the gates. By this means the opening through which the type is pushed corresponds to the thickness of the type-body which the hammer is adjusted to eject.

In the key-board, we have said, we by preference use sixty keys, though we do not limit ourselves to this number, as we find that one hundred and eighty letters and characters are all of a single font commonly used, being nearly all of the printer's case. We have in the machine shown in Fig. 2 used sixty keys.

25 There are in a font of type, say, five letter A's, to wit: capital, lower case, small capital, and italic capital and lower case. The single key operates to push out into the carrier all these, and in addition thereto a figure, double 30 letter, or a mark, making six to each key-lever. We have explained the function of the short key-lever H^{10} , operated by the supplemental key H^9 , Fig. 13, and we have explained how the depression of the key H^8 of the lever H^5 35 actuates the mechanism to operate the hammer to expel the type standing before it and to adjust the movements of the hammer and the gate to the requirements of the type-body acted upon.

40 We have shown that a single key-lever operates to eject six characters. We have also found that the two movements of the hammer and gate, effected, as we have shown, by the pins t and t' and their co-operative connections are sufficient to handle these six characters. By these simple means we are able to effect a partial distribution of the one hundred and eighty characters into thirty classes of six characters each. We shall next 45 show how a further and final distribution is effected.

50 The key-lever H^5 carries upon the end opposite to the fulcrumed end a pin, on which is a friction-roller I , acting upon the face of the cam I^4 . (Shown in Figs. 4, 11, and 12.) This cam I^4 is supported on the shaft I^2 . This shaft is supported at its lower end by the piece I^5 , attached to the frame A, and the other extremity by the piece I^6 , also attached 55 to frame A, one of which pieces I^6 is shown in Fig. 1 attached at I^6 . The effect of depressing the key-lever is to cause a partial rotation of the shaft I^2 as the friction-roller moves down the face of the cam. This shaft 60 to frame A, one of which pieces I^6 is shown in Fig. 1 attached at I^6 . The effect of depressing the key-lever is to cause a partial rotation of the shaft I^2 as the friction-roller moves down the face of the cam. This shaft 65 is one of thirty, as shown, and the operation of one will illustrate that of all, as they are in all respects similar. Each of these shafts

carries an arm I^3 , attached near its upper end, as in Fig. 11 at I^3 . The other extremity of this arm I^3 carries the piece I^{50} , having a carrier at its lower end. When the key-lever H^5 is depressed and the partial rotation of shaft I^2 effected, as just explained, this piece I^{50} 70 swings to the position shown in the dotted lines, Fig. 11. The arrival of carrier K to the position shown is coincident with the completion of the movement of the hammer to push out the type at the end of the line. The effect of these coincident movements is to land the type within the carrier K, standing, as in 75 channel D, on its feet. The moment the key H^8 , Fig. 11, is released by the finger the coiled spring I^7 on shaft I^2 carries back the arm to the position as seen at I^8 . As will be seen in Fig. 5 at I^8 , the dotted line shows the 80 path of movement of the carrier K to be the arc of a circle. All the carriers K are so arranged that these arcs coincide at the point where the pusher thrusts out the type, so that each carrier gets its type whether the arm 85 carrying it be long or short. This is obvious from Fig. 5, where a number of them are shown; also, in Fig. 2, where thirty are shown. It will be seen that the arms are arranged along two sides of an acute angle. Compactness and rapidity of operation are best attained by having this angle something less than ninety degrees. The plate E, as shown 90 in Figs. 2 and 5, is a hard and smooth piece of metal on which the type conveyed in carrier K, which is open at its lower extremity, slide, standing on end as the arm swings back to its position, as seen in Figs. 2 and 5 at I^8 . Arranged in this plate E directly under the lower end of these carriers K, which are open 95 at the lower end, as explained, as they stand in the position shown in Fig. 2, are openings e to correspond with the size of type-body the carrier has brought. As soon as the carrier K reaches this position the type within it 100 falls through its corresponding opening in plate E into a channel directly beneath, one of which is shown in section in Fig. 11 at I^9 . Through this channel I^9 the type drops into the opening e' , directly beneath it, in plate 105 E', Fig. 11, and through this plate and through the channel E^3 to its final resting-place in the grooved plate F, Fig. 11. The plate E^2 (shown in Fig. 3) has a series of channels I^9 , which serve only to direct the falling type to 110 the opening in plate E'. In plate E^2 there are as many channels I^9 as there are carriers K bringing type. This plate E^2 is rigidly attached to plate E and is held in position by it. Directly below the lower edge 115 of E^2 is the switch-plate E' , Figs. 3, 6, and 11. By means of this switch-plate the second step in the distribution of the type is effected. On emerging from the channels I^9 in plate E^2 the type enter the openings e' 120 in the plate E' , Figs. 5, 6, and 11. It will be seen in Fig. 5 that there are six rows of holes e' , of thirty each, corresponding to the six letters and characters, as explained above, 125 130

delivered by each carrier K. The line of these holes is made to conform to the line of the holes of exit in E² above, from which the type emerge as they descend, as just explained. This switch-plate E' is supported on the movable frame E⁰, Figs. 3 and 23. This frame rests on its two extremities on the projections E⁰⁰ of the frame A, and its middle part upon the piece E⁰⁰⁰, attached to the frame A at e³, Fig. 3. The two projections E⁰⁰ and the piece E⁰⁰⁰ carry friction-wheels E^X, upon which the frame E⁰ moves, Fig. 3. Normally, or in ordinary work, the line of holes e' numbered 1, Fig. 6, stand under the exit-mouth of the channels in plate E² and serve to receive the lower-case letters and such other figures or characters as may be desired, which thence pass through the elastic tubes E³ into the grooved plate F. If capital letters are being distributed, the line of holes e' numbered 2 is brought under the channels in E² and receive the type as they emerge therefrom, and so pass through the openings of line 2 and through elastic tubes E³ into the grooved plate F below. When the other letters, as small capitals or italic caps or lower case, are being distributed, the line of holes 3, 4, 5, and 6, intended to receive them, is brought under the channels in plate E² and serves to conduct by the elastic tubes E³ the falling type into their proper grooves in plate F. The movement of the frame E⁰, carrying plate E', to bring the holes therein to the positions just described is effected by five keys, seen in Fig. 6 at E⁶, and numbered 2, 3, 4, 5, and 6 to correspond with the line of holes. Since the line of holes that receives the lower case normally stands under the channels E², no key is needed. Key number 2 on being depressed moves the frame-carrying plate E', so that the line of holes No. 2 comes in position to receive the descending type—say capitals—and so of the other keys respectively. As seen in Fig. 17, which is a section of the machine at y y, Fig. 6, the key is part of a piece E⁶ held on the shaft E⁸, which shaft is supported by bearings attached to the frame A at E⁹. E⁶ is pivoted at e⁵ to the piece e⁶, which at its other extremity is hooked over a piece e⁷ in arm E¹⁰, carried by the rocker-shaft E¹¹. Each of the five keys is in the same way attached to rocker-shaft E¹¹, as seen in Fig. 6. The depression of one of the numbered keys E⁶ partially rotates this rocker-shaft, and thereby actuates a single arm E¹², Figs. 6 and 17. The outer end of this arm E¹² is pivoted to the rod or piece E¹³, which at its other end is attached to the frame E⁰ at E¹⁴, Fig. 6. It will be seen that the depression of any of the numbered keys, Fig. 6, partially rotates the rocker-shaft E¹¹, and so actuates E¹³ to draw the movable frame E⁰ toward the operator.

In Fig. 17 at f is seen pivoted to an arm opposite to the arm e⁶, carried by the shaft E⁸, the piece f', the opposite end of which is pivoted at f² to one arm of the bell-crank lever

f³, which is pivoted to the projection of the frame A, (marked E⁰⁰.) The other arm of this bell-crank lever is pivoted at f⁴ to the movable pin f⁶ and actuates it. Through this mechanism the depression of key 2, besides actuating the movable frame E⁰, as explained, causes the bell-crank lever f³ to move so as to throw the pin f⁶ in front of the moving shoulder f⁵ on the frame E⁰, Fig. 6. The movement of the pin f⁶ is timed to arrest the frame-carrying plate E' at a point when the line of holes in plate E' number 2 are in position to receive the type descending through the channels of the plate E². By a similar mechanism key 3 would bring the line of holes marked 3 in position to receive the type intended for them, and to arrest its movement when it has reached its proper position. In like manner the other keys bring their respective lines of holes in position to receive the type intended for them and arrest it there. The coiled spring f⁷ returns the frame to the normal position when the key is released by the finger, and the coiled spring f⁸ restores the key to the position in which it stood before depression. The piece f⁹ is a rod bent to receive and hold one end of the coiled spring f⁸, and at its two extremities is attached to the frame A.

As before explained, the rows of holes in the plate E' are brought, as required, in line under the channels E² by depressing the levers 2, 3, 4, 5, and 6, as required by the kind of letters being distributed. These holes (seen in this plate, Fig. 6) are the openings or mouths of the tubes E³, (shown in Figs. 1 and 3,) which are attached to the lower side of E', so that each is a continuous channel from said plate to some groove designated for the particular letter which that channel conducts. In order that this plate E' may move freely, it is necessary that the tubes E³ should be flexible and elastic. This we effect by making them of coiled wire formed into the proper shape to allow the type which it is to convey to pass freely without turning round or getting out of position as they fall into place, as seen in Fig. 11. Plate E', Figs. 6 and 11, may be made of a single piece; but for convenience of attaching the tubes and of removing the same, should it become necessary, we have preferred to make them in pieces, as shown in Fig. 6, in which each piece is made separate and removable, the ends resting on part of the movable frame E⁰ in Figs. 3 and 23. The tubes, preferably of coiled wire compressed upon a former to the proper size, afford all the flexibility and elasticity required and allow the type to fall through them freely. The wire tubes for convenience are attached to a piece of thin metal, formed as shown in Fig. 22. The upper end is held in the plate E' by its enlarged end.

The lower end of the wire tube E³ is attached to a piece shown in Figs. 19 and 20. The upper part of this piece in Fig. 19, at m², is bent around the lower end of the wire tube and holds it firmly. The lower end m³ is

- bent to form a hook, which, as seen in Fig. 23, engages with the piece m^4 , attached to the grooved plate F at m^5 . The elasticity of the tube E³ holds the hook m^3 in position.
- 5 When the type has descended into its appropriate groove in plate F, Fig. 11, standing on its feet, as seen in Fig. 18 at n, it must be pushed forward in order to admit the one following it into the same groove. This is effected by a hammer or pusher F' for each groove or channel, as seen in Figs. 3, 11, and 18. They are arranged on the shaft F², which actuates them to move each time a key is depressed slightly forward sufficient to 15 push forward any type that may stand before any one of them. There is one of these hammers at the upper end of each groove or channel and prevents the type that has descended into position falling out, as seen in 20 Fig. 18. The plate F is given a little descent, so that the type in the channels, when righted upon their feet, lean away from the hammer. For convenience and compactness there should be four plates F, each grooved 25 to carry one-quarter of the number of characters to be distributed, as shown in Fig. 1. In our machine now shown, which we have tried and found very convenient, each plate has forty-five grooves or channels. The two upper plates F, Fig. 1, are to contain the most used characters, and the two lower ones those less frequently required. When one of these channels becomes full, the type are slid into a movable channel and removed to the setting-machine. Motion is given to the shaft F², which carries the hammers F', by the arm g, Fig. 3, which is pivoted at its outer end to the rod g'. This rod g' is pivoted at its upper end to the arm g² on a rocker-shaft g³, 40 having at its other end an arm g⁵, to which is attached the rod g⁴, the upper end of which is pivoted to the arm h⁷ H¹², attached to the shaft H³, Figs. 13 and 3. We have explained how the key-board H⁵ actuates the shaft. When 45 any key of the key-lever is depressed, motion is given to the arm g⁵, which is connected to the shaft F², as explained, and so to the hammers acting at the upper end of the channels in the grooved plate F, so that the movement 50 of any key actuates all the hammers.
- What we claim, and desire to secure by Letters Patent in type-distributing machines, is—
1. The lifting-piece D², the pusher D¹¹ and channel D, in combination with the automatically-adjustable hammer and gate H' H², as described, and for the purposes set forth.
2. The lifting-piece D², in combination with the rack D³, the pinion D⁴, the rack d, the lever d⁴, having a friction-roller d¹³, the cam d³, shaft d⁰, and the crank c³ d², substantially as described, and for the purposes set forth.
3. The combination of the pusher D¹¹, the lever d⁹, having the friction-roller d¹², with the cam d⁸, shaft d⁰, and crank c³ d², substantially as described, and for the purposes set forth.
4. The combination of the lifting-piece D² and the rack D³ with the pinion D⁴, rack d, lever d⁴, and spring d⁶, substantially as described, and for the purposes set forth.
5. The combination of handle d² and the crank c³ with sleeve c', spring c², and spring c, all operating together substantially as set forth, and for the purposes described.
6. In combination, the hammer H, piece h², arm h³, shaft h⁴, arm h⁵, the piece h⁶, the arm h⁷ H¹², mounted on the rock-shaft H³, and piece H⁴ with the key-lever H⁵, substantially as described, and for the purposes set forth.
7. The combination of the automatically-adjustable hammer H⁶, pivoted pieces H' H², piece b, arm b², shaft b⁴, arm b⁶, the piece b⁷, arm b⁹, shaft b¹⁰, and the pieces b¹² and b¹³ with the key-lever H⁵ and H¹⁰, having the friction-rollers t t', as and for the purposes described.
8. In combination, the carrier K with the plate E, the channels I⁹, the switch-plate E' with the tubes E³, and grooved plate F, substantially as described, and for the purposes set forth.
9. The combination of the carrier K, the shaft I², and cam I⁴ with the key-lever H⁵, having the friction-roller I, substantially as described, and for the purposes described.
10. The combination of the pusher F', shaft F², arm g, rod G', arms g², mounted on shaft g³, rod g⁴, arm h⁷ H¹², mounted on shaft H³, with the key-lever H⁵, and the piece or rod H⁴, lying below and at right angles and close against the under edge of the lever H⁵, substantially as described, and for the purposes set forth.
11. The combination of the switch-plate E' with rod or piece E¹³, arms E¹⁰ and E¹², mounted on shaft E¹¹, piece e⁶, and lever E⁶, substantially as described, and for the purposes set forth.
12. The combination of the switch-plate E', rod or piece E¹³, arms E¹², mounted on shaft E¹¹, piece e⁶ and E¹⁰, the lever E⁶ with the piece f', bell-crank lever f³, and pin f⁶, substantially as described, and for the purposes set forth.
13. In a type-distributing device substantially as described, an automatically-adjustable hammer combined with a gate for controlling the ejection of the type, and a key-board, and mechanism, substantially as described, between the hammer and key-board, as set forth, whereby the type can be classified according to the thickness of their bodies, substantially as described.
14. In a type-distributing device substantially as described, the combination of a key-board and its connections, and mechanism, substantially as described, between the hammer-gate and key-board, as set forth, with the adjustable hammer and gate, the carrier K, and a switch-plate, as and for the purposes described.
15. The combination, in a type-distributer, of a key-board, its connections, and mechanism, substantially as described, between the hammer-gate and key-board, an automatically-adjustable hammer, a gate, a switch-

plate, and elastic tubes, and type-receiver, substantially as set forth, whereby the type are taken from the galley and distributed, substantially as described.

5 16. The automatically-adjustable hammer H and pivoted piece H' and H², as described, and for the purposes described.

In testimony whereof we affix our signatures in presence of two witnesses.
